UNITED STATES PATENT OFFICE.

JOSEPH AUGUST, OF BOSTON, MASSACHUSETTS.

FIRE-EXTINGUISHER.

1,297,310.

Specification of Letters Patent. Patented Mar. 18, 1919.

Application filed January 24, 1918. Serial No. 213,550.

To all whom it may concern:

Be it known that I, JOSEPH AUGUST, a citizen of the United States, residing at #200 Columbus avenue, Boston, in the 5 county of Suffolk and State of Massachusetts, have invented new and useful Improvements in Fire-Extinguishers, of which the following is a specification.

It is a well known fact that tetra-chlorid 10 of carbon is one of the most efficient agents for extinguishing fire. In view of this it has been tried on numerous occasions to charge the conventional fire extinguisher with this agent, instead of the present 15 chemical solution used. It was found, however, that this was impracticable due to the fact that the carbonic acid gas mixed with the tetra-chlorid of carbon causing very unsatisfactory results.

20 In as far as is known, nitrogen is the only gas which will not mix with tetra-chlorid of carbon and I have therefore conceived the idea of charging a fire extinguisher with nitrogen gas under pressure 25 and tetra-chlorid of carbon, the former serving to eject the latter from the extinguisher.

One convenient employment of my invention is disclosed in the accompanying 30 drawing in which the figure discloses a sectional side elevation of a hand fire extinguisher, charged in accordance with my idea.

Referring more particularly to the drawings, it will be seen that the reference A 35 designates the container which is entirely closed at the bottom, but is provided with a small opening at its upper end through which a tube B projects which tube extends to within a half inch of the bottom of the 40 container and is open at such end. The opposite end of the tube B projects beyond the top of the container A and is provided at this end with a hand control valve C. D designates an inlet through which communica-

tion may be had with the interior of the 45 extinguisher and by means of which said extinguisher may be charged, with both nitrogen and tetra-chlorid although I wish it understood that any suitable means of introducing these agents into the interior 50 of the extinguisher may be employed.

E discloses the position which the tetra-chlorid of carbon occupies and F the nitrogen, which, by virtue of being lighter than the tetra-chlorid of carbon, occupies the 55 uppermost position within the extinguisher.

It will, of course, be understood that the nitrogen is introduced to the interior of the extinguisher under pressure and that any convenient pressure may be used, al- 60 though I have found that the best working pressure averages from 75 to 100 pounds per square inch.

Although I have disclosed my idea of utilizing nitrogen as an expelling agent for 65 tetra-chlorid of carbon in a hand extinguisher, I wish it to be understood that the use of the same is not limited to this type of extinguisher, but may be utilized in any form more convenient. 70

Having described my invention what I claim is:

1. Tetra-chlorid of carbon and nitrogen in direct contact in a fire extinguisher, the nitrogen being introduced and stored there- 75 in under pressure and serving as an expelling agent for the tetra-chlorid of carbon.

2. A fire extinguisher including a conventional tank and discharge tube extending to the lowermost part of said tank, the 80 lower portion of the tank being filled with tetra-chlorid of carbon and an expelling agent located above such tetra-chlorid of carbon and being in direct contact therewith such expelling agent being nitrogen 85 gas.

JOSEPH AUGUST.
